UNITED STATES PATENT OFFICE.

CHARLES J. KINDEL AND HENRY W. LUNDBERG, OF GRAND RAPIDS, MICHIGAN, ASSIGNEES TO FOOTE-REYNOLDS COMPANY, OF GRAND RAPIDS, MICHIGAN, A CORPORATION OF MICHIGAN.

EXTENSION BED.

Application filed June 14, 1926. Serial No. 115,837.

This invention relates to an extension bed and, more particularly, to a bed which is provided with two separate and distinct spring structures, one of which in the contracted form of the bed is located underneath the other but which may be extended and then elevated into the same plane with said other and upper spring, a mattress normally folded and carried upon the upper spring in the contracted position of the bed being unfolded so as to cover both springs.

The present invention is concerned with the simple and economical production of a construction of the type described which may be of double bed width when it is to be used as a bed and then contracted to one half of said width during the day when it is not in use, with consequent saving of space. This is a matter of importance in a great many places, particularly in apartments where space is a matter of considerable import.

The invention consists in many novel details of construction and arrangement of parts for effectively attaining the ends stated all of which, together with many others not at this time specifically set forth, will appear as understanding is had of the invention from the following description taken in connection with the accompanying drawings, in which

Fig. 1 is a transverse vertical section through the structure when extended for use as a double bed.

Fig. 2 is a like section showing the same when not in use, the width thereof being reduced one half.

Fig. 3 is a plan view of the bed structure, the springs being removed so as to fully show the construction and the means whereby the extension frame is equalized in its inward and outward movements.

Fig. 4 is a front elevation of the lower part of the bed with the lower spring positioned underneath the upper spring, the front covering panel being removed to disclose the construction, and

Fig. 5 is a view similar to Fig. 4 the lower spring being moved outwardly and elevated to upper position.

Like reference characters refer to like parts in the several figures of the drawings.

In the construction of the bed a bed frame is provided having ends each of which in-

cludes two spaced apart vertical posts 1 connected in any suitable manner by cross members 2 which may be of various types and designs. Adjacent the inner corner of each of the posts a vertically positioned block 3 is secured around which is placed and secured vertical angle bars 4. Between the rear posts 1 of the bed frame a panel 5 is located and in practice is detachably connected to the posts between which it is disposed so that, for shipment, the construction may be knocked down to occupy as little space as possible.

Between the ends of the bed frame a horizontal frame, preferably made of commercial forms of iron, is disposed. It includes an upper rectangular frame member having a rear angle bar 6, a front angle bar 7 parallel thereto, two parallel end connecting bars 8 with diagonal braces 9 at the corners of the frame member for holding the same rigid. Directly below the bar 6 and spaced a distance therefrom is a second angle bar 6^a paralleling the bar 6 and forming the rear side of a second rectangular frame member which is completed by two end angle bars 8^a lying directly below the bars 8 and a front flat bar 10 which is located in a plane a short distance back of the upper bar 7.

The upper and lower rectangular frame members are connected together by vertical angles 11 which are permanently secured to the bars 8 and 8^a a short distance inward from each end thereof and so located that their outwardly extending flanges will pass alongside of the flanges of the angle bars 4, previously described. Headed pins 12 projecting from the flanges of the angle bars 4 to be received in suitable slots cut in the outwardly extending flanges of the angle bars 11. This specifically forms no part of the present invention but is fully disclosed in a copending application for Patent Serial No. 117,573, filed June 21, 1926, by Charles J. Kindel.

The upper frame member comprised of the bars 6, 7, and 8 serves as a support for a spring structure 13 above which a mattress 14 may be placed. A second mattress 15 is connected at one edge to the front edge of the mattress 14 by a strap or band 16 whereby the mattress 15 may be readily folded over to lie above the mattress 14, as shown in Fig. 2.

It is evident that the space between the upper and lower rectangular frame members is open at the front side and in said space an extension frame is mounted so that it 5 may be drawn outwardly when desired or pushed back so as to lie entirely within the space. This extension frame is of rectangular form also. It is made of front and rear parallel angle bars 17 connected by end 10 bars 18 while at each corner a vertical post 19 also of angle bar form is permanently secured at its lower end, the same extending upwardly nearly to the lower side of the bars 8 of the first described upper rectangular frame member. At the front side of 15 the extension frame a panel 20 is located and permanently secured to the front posts 19 it having substantially the same form and appearance as the rear panel 5, previously described. Castors 21 are secured at the front corners of the extension frame to permit its easy outward and inward movement, it being understood that the inwardly extending portions of the extension frame are 20 carried on the bars 8^a which serve as supporting guides therefor. The inward and outward movement of the extension frame is 25 equalized by means of the following structure:

Two links 22 are pivotally connected at 30 their rear ends to the flat bar 10, as best shown in Fig. 3. Two additional links 23^a are pivotally connected at their front ends to the front bar 17 and are pivotally connected at their rear ends to the links 22 a short distance back of the front ends of 35 said links. The projecting forward portions of the links 22 extending beyond carry stops 22^a which in the fully extended position of the extension frame come against edges of the links 23^a, as shown in Fig. 3, and limit 40 the outward movement of the extension frame. A connecting bar 24^a is disposed between the pivotal points of connection of the links 22 and 23^a, all being fully shown 45 in Fig. 3. With this structure the extension frame may be moved inward and outward very readily and each end thereof will move in unison with the other and have an equal movement.

On the extension frame a vertically adjustable spring carrying frame is mounted. This spring carrying frame is of rectangular form having longitudinal spaced apart rear and front angle bars 23 connected at their 55 ends by parallel end bars 24, the ends of which overlap the horizontal flanges of the bars 17 of the extension frame. All of the rectangular frame members described are provided with diagonal braces at their corners like the braces 9 first described. A 60 spring structure 25 is carried by the spring supporting frame, it being of the same type as the spring structure 18.

The spring carrying frame with the spring

thereon is designed to be elevated to an 65 upper position or lowered from said upper position to its lower position. To effect this a link 26 is pivotally connected at one end adjacent one end of the vertical flange of each of the bars 17 (see Fig. 5). An additional link 27 is pivotally connected at one end to the vertical flanges of each of the bars 23, the pivotal points of connection of the links 26 and 27 being substantially 70 in vertical alignment. The links 26 and 27 are pivotally connected together, and each link 27 is formed with a curved extension 75 27^a beyond the point where it is pivotally connected to the link 26. Adjacent the opposite end of each of the bars 23 another 80 link 28 is pivotally connected at one end and at their opposite ends these links are pivotally connected to bars 29 which at their lower ends are pivotally connected to the vertical flanges of the bars 17. The bars 29, as shown in Fig. 5, extend upwardly from the bars 17, are thence reversely curved as indicated at 30 and then extend upwardly as at 31 there being a connecting board 32 between the upper ends of the extensions 31 which lies transversely of the length of the spring 25. In lower position the bars 31 are as shown in Fig. 4, and the connecting cross board 32 lies against the upper side of the spring structure 25. Long connecting rods 33, one at each side of the spring supporting frame, connect the ends 27^a of links 27 with the curved sections 30 of bars 29, as shown in Fig. 5.

The bed being in contracted position, as 100 shown in Fig. 2, it is necessary merely to withdraw the extension frame by pulling outward on the panel 20 until the stops 22^a engage against the links 23^a. Then the cross board 32 is grasped and turned from 105 the position shown in Fig. 4, upwardly and to the right to the position indicated in Fig. 5. This will cause a straightening of the toggles made by links 28 and 29 and, simultaneously, by reason of the connection made by the bars 33, the toggles made by links 26 and 27 will be straightened lifting the spring carrying frame and the spring 25 to the upper position shown in Fig. 5. The engagement of sections 30 of the bars 110 29 with the ends of bars 24 limits the extent of upward movement and when this occurs the knuckles of the toggles will have passed from one side to the other of their dead center lines so that the application of weight to the springs 25 will have 115 no effect except to force said sections 30 more strongly against the bars 24. The board 32 will then be in substantial vertical position and may serve to all intents and purposes as a head board for the bed. At 120 least, it will not be in the way. The mattress 15 is unfolded from the mattress 14 so 125

as to lie upon the spring 25 or in the position shown in Fig. 1.

To lower the spring 25 and its supporting frame it is necessary merely to reverse the 5 operation, that is, grasp the board 32 and move it from the position shown in Fig. 5 downwardly and to the left, the spring supporting frame lowering on this movement. The angle posts 19 serve as guides for the 10 upward and downward movements of the spring supporting frame. It will be noted that on the clockwise movement of the extensions 31 to links 29 from the position shown in Fig. 4 to that shown in Fig. 5, there is an apparent application of force to 15 the links 28 which would serve to move the spring supporting frame to the right against the right hand posts 19. This, however, is neutralized by reason of the links 26 which 20 extend from their end pivot points to the left to connect to the links 27. The spring 25 with its supporting frame will move vertically upward and downward without any endwise movement which would bring 25 the spring supporting frame frictionally against any of the vertical guide posts 19.

The construction described is simple, durable and practical. A double width bed is produced and one which when not in use 30 may be contracted to fifty per cent of its width when in use. This bed construction has been fully developed and tested and has proved thoroughly practical in actual practice. The invention is defined in the 35 appended claims and is to be considered as comprehensive of all forms of structure coming within their scope.

We claim:

1. In a bed having a stationary frame 40 adapted to carry a spring, an extension frame mounted below said stationary frame and movable outward and inward with respect to the same, a spring carrying frame carried by said extension frame on which a 45 second spring may be carried, vertical guides at the corners of the extension frame within which the spring carrying frame is located, a pair of toggle links pivotally connected together at each end and at each side 50 of the spring carrying frame, one of the links of each pair being pivotally connected at its end to said spring carrying frame and the other link of each pair of links being pivotally connected to the extension frame, 55 said links connected to the extension frame at one end thereof being extended beyond their points of pivotal connection to their companion links, a bar disposed between and connected to the ends of said extensions 60 adapted to be manually engaged to thereby straighten the two pairs of links at one end of the said frames, and an elongated link at each side of the extension frame connecting the toggle links together whereby manual 65 operation of the pairs of toggle links at one

end of said frames will simultaneously and equally operate said pairs of links at the other end of said frames, substantially as described.

2. In combination with a bed having a 70 horizontal supporting frame, and a horizontal spring carrying frame vertically movable relative thereto, a long lever pivotally connected to the supporting frame near one of its ends, a corresponding long lever pivot- 75 ally connected to the spring carrying frame near its opposite end, short levers pivotally connected respectively to the spring carrying frame and to the supporting frame near their respective ends, said short levers being 80 pivotally connected to said long levers intermediate their ends, a connecting rod connecting the respective free ends of the long levers for the purpose of effecting vertical movement of the spring supporting frame 85 and counteracting longitudinal thrust there- of.

3. In combination with a bed having a horizontal supporting frame and a horizontal spring carrying frame vertically 90 movable relative thereto, pairs of toggle levers connected to the supporting frame and spring carrying frame at opposite sides and near the respective ends thereof, one of the arms of each pair of toggle levers near 95 one end of the bed and at opposite sides thereof being extended upward and connected by a cross member to provide a folding head rest for the bed and an operating member for the toggle links, and connect- 100 ing rods connecting the toggle levers at opposite sides of the bed whereby they are simultaneously operated.

4. In a bed having a horizontal support- 105 ing frame and a horizontal spring carrying frame vertically movable relative thereto, a long lever pivotally connected to each side of the supporting frame near one of its ends, said long levers extending upward and being provided with a cross member to serve as a 110 folding head rest and actuating member, a long lever pivotally connected at each side of the spring carrying frame near its ends opposite the first mentioned levers, short levers pivotally connected to the respective 115 sides of the supporting frame and the spring carrying frame and also pivotally connected to and between the ends of each of said long levers and connecting rods connected to said long levers beyond their points of connection 120 with the short levers at the respective sides of the structure whereby all of the pairs of levers will be caused to move simultaneously to effect raising of the spring carrying frame without tendency for longitudinal 125 movement.

In testimony whereof we affix our signatures.

CHARLES J. KINDEL.
HENRY W. LUNDBERG.
